UNITED STATES PATENT OFFICE.

GUSTAVE ADOLPH M. LILJENCRANTZ, OF CHICAGO, ILLINOIS.

FRUIT-JAR OPENER.

SPECIFICATION forming part of Letters Patent No. 285,048, dated September 18, 1883.

Application filed August 2, 1883. (No model.)

To all whom it may concern:

Be it known that I, GUSTAVE ADOLPH M. LILJENCRANTZ, of Chicago, in the county of Cook and State of Illinois, have invented certain new and useful Improvements in Instruments for Opening Fruit Jars and Bottles; and I do hereby declare that the following is a full, clear, and exact description of the invention, which will enable others skilled in the art to 5 to which it appertains to make and use the same, reference being had to the accompanying drawings, and to letters of reference marked thereon, which form a part of this specification.

Great difficulty is often experienced by 15 housekeepers and others whose business requires them to open jars or bottles of preserved fruits, because of their inability to overcome the friction of the cap or cover caused by the suction due to the shrinkage of the fruit, or 20 from other causes.

The object of my invention is to furnish means for easily removing the said cap or cover of fruit-jars, and this I accomplish by two instruments, viz., a wrench to unscrew 25 the cap or cover, and a strap and buckle device to hold the bottle or jar firmly in one position while said cap is being removed, substantially as hereinafter fully described, and as set forth in the drawings, in which—

30 Figure 1 is a plan view of my buckle. Fig. 2 is a vertical longitudinal section of the same with the strap in position, showing the manner of its use. Fig. 3 is a plan view of my wrench, and Fig. 4 is a vertical longitudinal 35 section of the same, together with a plan view of the buckle and strap, illustrating the manner of their combined use.

In the drawings, A represents a buckle, having side bars, *a a*, four cross-bars, 1, 2, 3, 40 and 4, and a handle, A', extending longitudinally from one end thereof. B represents a strap or band of suitable material, used in connection therewith.

When it is desired to use the above-mentioned buckle and strap the latter is first 45 slipped upward between the bar 4 and the handle, then between cross-bars 4 and 3, up again between 2 and 3, down between 4 and the handle, around the bottle on a horizontal plane, 50 up between 2 and 3, and then down between 1 and 2, under bar 1. It will be noticed that the strap between cross-bar 4 and the handle

and under cross-bar 1 laps over onto itself; therefore, when it is desired to use the same, and the handle is oscillated outward, (the bar 55 1 serving as the fulcrum, and bar 4 the point of greatest resistance,) the lateral and tensile strain on the strap will prevent it from slipping the buckle, and at the same time tighten its grip on the jar or bottle. If desired, however, bar 4 may be dispensed with, in which event the strap would be looped around bar 3, back onto its length, and there riveted, thus connecting it to the buckle, so that there would be less likelihood of either part being 65 lost to the other when not in use.

I do not limit myself to the buckle as above described, as it is obvious other forms may be substituted, which, when used in combination with the wrench, would answer my purpose, 70 although not quite so well.

The wrench consists of a trough-shaped bar, C, open at both ends, one end of which is bridged over. The stock D of this bridge is extended longitudinally and terminates in two 75 arms, *d*, diverging obliquely to either side of the same, and placed at about an angle of forty-five degrees to each other. These arms have extending downward from their extremities the studs *d'*, which bear against the periphery of the cap of the jar, and at a distance apart corresponding to about one-third the circumference of the smallest size cap.

In the channel or trough of the bar C operates longitudinally the tang F of the jaw G. 85 This tang passes under the bridge D, out from the open contiguous end of said trough, where it terminates, and is enlarged and extended downward to form the jaw G, which latter, when in use, bears against the circumference 90 of the jar-cap at a point intersected by a line equally dividing the angle described by the arms *d*. On that part of the upper surface of the tang F which moves within the trough of the bar C is a raised part or protuberance, *e*, 95 against which the operator presses his thumb or finger when adjusting the wrench around the periphery of the cap. As nearly all the caps of fruit-jars have a side projection of one kind or another, the jaw G will, as it is being 100 turned to unscrew or remove the cap, meet and bear laterally against the same. The strain, therefore, will be laterally on the tang, so that very little pressure of the thumb on the pro-

tuberance *c* is needed to prevent the jaw *G* from moving longitudinally backward and slipping said projection.

What I claim as new, and desire to secure by Letters Patent, is—

1. A buckle, *A*, as described, having a handle, in combination with a suitable strap or band, as set forth.

2. The combination, with a wrench having two diverging arms, with studs extending downward from the extremities thereof, and having a jaw, *G*, the whole adapted to grasp the periphery of a fruit-jar cap or cover, of a buckle having a handle and strap connected therewith, adapted to hold the body of said jar while the cap is being removed, substantially as specified.

3. A buckle having preferably three or four

cross-bars connecting the side frame, and having a handle rigidly fixed to and extending longitudinally from one end thereof.

4. A buckle having a handle, as hereinbefore described, and having four cross-bars connecting its side frames, the spaces between the second and third of which, and between the fourth and the handle, being preferably wider than the other, and the end cross-bar of which, when in operation, serves as a fulcrum.

In testimony that I claim the foregoing as my own, I hereunto affix my signature in presence of two witnesses.

GUSTAVE ADOLPH M. LILJENCRANTZ.
